FORM GRINDING MACHINE

Frederick A. Ward, Highland Park, Mich., assignor to The Gear Grinding Machine Company, Hamtramck, Mich., a corporation of Michigan

Application January 6, 1941, Serial No. 373,352

5 Claims.

(Cl. 51—52)

The invention relates to grinding machines of that type in which a formed grinder wheel successively operates on different portions of the work to repeat the pattern in the surface thereof. More particularly, the invention is designed for use in the grinding of gears but it is also applicable to many other uses.

Grinding machines designed for the form grinding of gear teeth generally consist of a work support, a grinder wheel movably mounted in relation to the work to perform the grinding operation thereon, a trimming mechanism for forming the grinder wheel, and an indexing mechanism through which the teeth of the gear are successively presented in operative relation to the formed grinder wheel. Inasmuch as the teeth are successively ground, the time required for the completion of the gear is proportional to its number of teeth. Thus with gears having a large number of teeth, a considerable interval of time is required for the completion of the work.

It is the object of the invention to expedite the completion of the gear by the provision of a plurality of grinder wheels which simultaneously operate upon different portions of the work. This will divide the time interval for the completion of the work by the number of separate grinder wheels thus employed. It is, however, absolutely essential that the surfaces ground by the separate wheels should exactly correspond in form and in indexed relation to each other. The invention, therefore, consists in the construction and organization of the grinding machine through which such result may be obtained.

In the drawings:

Figure 1 is a sectional front elevation of my improved grinding machine;

Figure 2 is a plan view thereof;

Figure 3 is a diagrammatic front elevation illustrating the hydraulic operating connections and controlling means therefor;

Figure 4 is a diagrammatic plan view;

Figure 5 is an enlarged end elevation showing the indexing mechanism and its operating connections;

Figure 6 is a plan view of Figure 5;

Figure 7 is a front elevation of a portion of Figure 5;

Figure 8 is a sectional elevation showing the locking and controlling means for the indexing mechanism;

Figure 9 is an end elevation of some of the elements shown in Figure 3;

Figure 10 is a plan view showing in full lines the trimming mechanism operatively arranged in relation to one of the grinder wheels and in dotted lines arranged in operative relation to the other grinder wheel;

Figure 11 is a side elevation, partly in section, of the carrier frame and trimming mechanism mounted thereon.

10 *General construction*

My improved grinding machine comprises generally a suitable base A on which is centrally mounted a rotatively adjustable work holder B, a plurality of mountings C and C' for separate vertically movable grinder wheels D and D', and an indexing mechanism E through which the work on the holder is successively rotatively advanced in relation to the grinder wheels. As specifically shown, there is only a single pair of grinder wheels D and D' but it is obvious that a larger number may be used if desired.

Where the gear to be ground has an even number of teeth, the grinder wheels D and D' may be positioned in the same plane on diametrically opposite sides of the work support. On the other hand, if the number of teeth is odd, then the plane of one of the grinder wheels must be at an angle to that of the other wheel corresponding to one-half of the circular pitch of the teeth. This necessitates means for adjusting one of the mountings, as for instance C', around the axis of the work holder, the amount of such adjustment depending upon various factors such as the diameter of the gear, the circular pitch of the teeth, etc. The machine is also provided with motors F and F' or other driving means for rotating the grinder wheels, a feed mechanism such as hydraulic rams G and G' for raising and lowering the grinder wheels in paths crossing the work, actuating means for the indexing mechanism such as a hydraulic motor H, and means for timing the alternate operations of said feeding mechanism and indexing operating mechanism. In addition to these elements, there is a trimming mechanism I for forming the grinder wheels together with means through which this mechanism may be successively arranged in operative relation to each wheel when said wheels are in proper angular relation to each other and to the work.

45 *Work holder*

The work holder B is preferably supported 50 on a circular grooved track B' of V-shaped cross

section engaged by a corresponding rib B^2 depending from the holder. The periphery of the holder is formed with a worm gear B^3 in mesh with a worm B^4 actuated by mechanism hereinafter described. The work, such as a gear wheel J , is mounted on a suitable supporting jig J' exchangeably mounted on the work holder B in axial alignment therewith.

Grinder wheel mountings

Each of the grinder wheel mountings C and C' comprises a column C^2 having a slideway C^3 thereon for a vertically movable carriage C^4 and at the upper end of this carriage is a horizontally extending guideway C^5 for a transversely movable carriage C^6 . A bearing C^7 on the latter carriage receives the arbor of the grinder wheel, said wheel being arranged in a plane passing through the axis of the work holder. Thus the movement of the carriage C^4 on the vertically extending slideway C^3 will carry the grinder wheel across the periphery of the work or gear wheel J . The carriage is actuated by the hydraulic ram G as will be hereinafter set forth.

Angular adjustment for grinder wheel D'

As before stated, where the gear to be ground has an even number of teeth, the grinder wheels D and D' may be arranged in a common plane on diametrically opposite sides of the gear to properly register with the teeth thereof. On the other hand, where the number of teeth is odd, the plane of one of these grinder wheels must be angularly displaced from the plane of the other wheel an amount equal to one-half the circular pitch of the teeth. To permit of such adjustment, the mounting for the grinder wheel D' is movably supported on the base A but is held at a fixed radial distance from the axis of the work holder by an arm K secured to the column C^2 and provided at one end with a bearing K' engaging a pin K^2 . This pin is secured to the base A in axial alignment with the work holder and, therefore, permits angular adjustment of the column and other elements of the grinder wheel mounting about this axis. As shown, the adjustment means comprises a bifurcated bracket K^3 on the base, having adjusting screws K^4 in the furcations thereof for engaging opposite sides of a finger K^5 secured to and projecting outwardly from the column C^2 .

Indexing mechanism

The rotative adjustment of the work holder to present successive teeth in proper registration to the grinder wheels is accomplished by an indexing mechanism including the worm wheel B^3 and worm B^4 . The indexing mechanism may be of any suitable construction but preferably, as shown, comprises a casing E containing a gear train E' connected at one end with a shaft E^2 which, through the medium of an intermediate shaft E^3 and beveled gear wheels E^4 is connected to a shaft E^5 on which the worm B^4 is mounted. The gear train E' includes one or more change gears and the opposite end of the train is connected to an external pinion H' which is actuated by the hydraulic motor H . This motor comprises a cylinder H^2 containing an elongated piston H^3 having a rack H^4 on one side thereof intermeshing with the pinion H' which latter extends through a slot H^5 in the central portion of the cylinder H^2 . The piston is moved in opposite directions by the fluid which is alternately admitted to opposite ends of the cylinder. There

is also a stop H^6 , preferably a screw threaded rod engaging one of the heads of the cylinder and adjustable therein to limit the stroke of the piston. The indexing mechanism also includes a notched wheel or disc E^6 which is engaged by a tapering locking dog E^7 to hold said disc and connected gear train in an exactly predetermined position. The dog E^7 is mounted on a rock arm E^8 which is actuated by a spring E^9 in a direction to withdraw the dog and is moved into locking position by a hydraulic motor E^{10} .

Operating mechanism

Electric motors F and F' have a driving connection respectively to the arbors of the grinder wheels D and D' which permits of the vertical movement of the carriages C^4 . As shown, this driving connection comprises a foldable frame F^2 carrying an intermediate pulley shaft F^3 driven by a belt F^4 from the motor and connected through a belt F^6 with a pulley on the arbor of the grinder wheel. The motors F and F' also drive hydraulic pumps L and L' which supply fluid under pressure to the feeding mechanisms. A third hydraulic pump L^2 , driven by a connection to one of the motors (not shown), supplies fluid under pressure to the controlling and timing mechanism for the feed mechanism and indexing mechanism. The sequence of operations performed by the machine are:

First, to reciprocate the carriages C^4 on their slideways C^3 , thereby simultaneously moving the grinder wheels D and D' across the work to perform their grinding operations thereon;

Second, to return these carriages to their original position;

Third, to stop or slow the movement of said carriages while the grinder wheels are out of contact with the work and to simultaneously operate the indexing mechanism to rotatively adjust the work holder. This completes the cycle which is repeated until all of the teeth of the gear are ground. The detail construction of this operating and timing mechanism may be varied but as specifically illustrated is as follows.

Controlling and timing mechanism

The hydraulic rams G and G' are supplied with operating fluid respectively from the pumps L and L' , and the fluid from the pump L passes through a conduit M to a valve M' and then through a conduit M^2 to a reversing valve M^3 . In one position of this valve the pressure fluid is directed through a conduit M^4 to the upper end of the ram G while simultaneously the fluid from the lower end of the ram is exhausted through a conduit M^5 also controlled by the valve M^3 . In the opposite position of the valve M^3 , the connections are reversed, pressure fluid passing through the conduit M^5 to the lower end of the ram and the exhaust fluid escaping through the conduit M^4 . Similar connections, designated by the same reference letters, are arranged between the pump L' and the ram G' . The operation of the reversing valves M^3 is through the medium of a hydraulic reciprocating motor N which is supplied with fluid from the pump L^2 and which, in turn, is controlled by a reversing valve N' . Fluid passes from the pump through a conduit N^2 to the valve N' and alternately to opposite ends of the cylinder of the hydraulic motor N through conduits N^3 and N^4 , said conduits also alternately carrying the exhaust fluid under control of the valve N' . The reciprocation of the motor N is communicated through a connecting rod N^5 to

rocker members N⁶ which reverse the valves M³. The pump L² also supplies pressure fluid through a conduit O to the hydraulic motor H which is under control of a reversing valve O'. This valve is operated by the hydraulic motor E¹⁰ through the medium of a mechanism including a lever O² directly connected to said motor E¹⁰ and which also actuates the rocker member E⁸ carrying the dog E⁷. The lever O² is connected by a link O³ with a rock arm O⁴ on a shaft O⁵. The shaft extends longitudinally of and at the rear of the base A and is connected through the medium of rock arms O⁶, links O⁷ and levers O⁸ with the valves M' controlling the passage of fluid through the conduits M and M². The shaft O⁵ is further provided with a rock arm O⁹ connected through a link O¹⁰ and bell crank lever O¹¹ with the reversing valve O'.

From the arrangement above described, it will be understood that the operation of the rams G and G' which raise and lower the grinder wheels is controlled by the hydraulic motor N while the hydraulic motor E¹⁰ controls the locking and unlocking of the indexing mechanism, the hydraulic motor H for actuating said indexing mechanism and the valves M' in the conduits supplying the operating fluid to the rams G and G'. The function of these latter valves is to restrict the flow of fluid to the rams during the period in which the indexing mechanism is operating so that during this time the grinder wheels will not be moved into contact with the work. It is, however, necessary to provide control means for timing the operation of the motors N and E¹⁰ so that the grinding operations of both grinder wheels D and D' will be completed and said wheels moved out of contact with the work before the indexing mechanism is unlocked and actuated to rotate the work into a new position, the construction being as follows. P is a bar mounted on the carriage C⁴ and extending parallel to the direction of movement thereof. P² and P³ are dogs adjustably secured to the bar P in spaced relation and P⁴ is an intermediate dog also adjustably secured to said bar. The dog P⁴ cooperates with a rocker member Q mounted on a column Q' rising from the base, said rocker member having two spaced fingers Q² and Q³, one of which is actuated by the dog P⁴ when the carriage C⁴ and bar P are moving in an upward direction, while the other finger is engaged by said dog when the said parts are moving in a downward direction. The rocker member Q is connected by a link Q⁴ with a valve R which controls the flow of pressure fluid from the conduit O through a conduit R' to the hydraulic motor E¹⁰. Thus when the dog P⁴ during its upward movement actuates the finger Q² and rocks the member Q, pressure fluid will be cut off from the conduit R' and the fluid in said conduit and in the hydraulic motor E¹⁰ is permitted to exhaust through the valve R. This permits the spring E⁹ to actuate the mechanism which unlocks the indexing gear train and operates the motor H. On the other hand, when the dog P⁴ is moving downward and actuates the finger Q³ to rock the member Q in the reverse direction, pressure fluid is supplied through the conduit R' to the motor E¹⁰ which locks the gear train. This motor E¹⁰ also operating through the connecting mechanism opens the valves M' to remove the restriction to flow of fluid through the conduits M and M². It further reverses the valve O' controlling the hydraulic motor H so that the piston of the latter is returned to its original position. Such return movement does

not, however, rotate the gear train E' as there is a one-way clutch H' between the shaft of the pinion H' and the end gear of the train.

The dogs P² and P³ which are on opposite sides of the dog P⁴ cooperate with a rocker member S which may, if desired, be coaxial with the rocker member Q but independent thereof. The rocker member S is connected through the medium of a rocker arm S' and connecting rod S² with a rocker arm S³ on a shaft S⁴. On this shaft S⁴ is a rock arm S⁵ which is connected to operate the reversing valve N' controlling the operation of the motor N which, in turn, actuates the reversing valves M' controlling the reciprocation of the rams G and G'.

Synchronizing means for the rams

The rams G and G' operate independently of each other to respectively feed the grinder wheels D and D' across the work. The speed of this feeding movement is dependent: first, upon the pressure against the piston of the ram, and second, on the resistance of the work due to the amount of material which must be removed by the grinding operation. Inasmuch as the resistance offered to the progress of the separate grinder wheels is not always the same, it is obvious that one of the rams might complete its movement in one direction in advance of the other ram. This, if uncorrected, would throw the two rams out of step with each other and with the indexing mechanism. To avoid such result, I have provided means which, while still permitting the two rams to move independently, prevents the reversal of direction of movement of either ram in advance of the other or before both have fully completed their downward strokes, the construction being as follows.

The reversing valve N' is connected by a link T with a lever T' which is normally locked against movement by a latch member T². Adjacent to the lever T' is a lever T³ which is connected by a link S⁶ with the rocker member S⁵. The two levers are resiliently yieldably connected to each other by spring pressed plungers T⁴ on the lever T' bearing upon opposite sides of the lever T³. In the locked position of the lever T', the valve N' is positioned so that the reversing valves M' supply pressure fluid to the upper ends of the rams G and G'. Consequently, while the lever remains locked, the rams can only move downward and if the one completes its movement in advance of the other, it will remain stationary. The operation of the dog P² upon the rocker member S and mechanism connected thereto will move the lever T³ and through the spring pressed plunger T⁴ will exert a pressure against the lever T' tending to move the latter in a direction to reverse the valve N'. Such reversal cannot, however, take place until the latch member T² is operated to release the lever T'. Such release of the latch T² is effected through the medium of an adjustable cam dog U on the carriage C⁴ for grinder wheel D' which just before the completion of the downward stroke of the ram G' actuates a mechanism connected to said latch. This mechanism, as shown, comprises a rock arm U' mounted on a rockshaft U² and having a roller U³ in the path of the cam U. The rockshaft U² carries a rocker arm U¹⁰ with a roller U⁴ for contacting with an elongated rocker member U⁵ on a rockshaft U⁶. The rockshaft U⁶ has a rock arm U⁷ connected by a rod U⁸ with a bell crank lever U⁹ connected with the latch T². The parts U', U², U³ and U⁴ are mounted on the support

ing column for the grinder wheel D' and are moved therewith about the axis of the work holder during adjustment for positioning said grinder wheel in relation to the work. The elements U⁵ U⁶, U⁷, U⁸ and U⁹ are mounted on the stationary base and by reason of the elongation of the rocker member U⁵, it will contact with the roller U⁴ in all positions of adjustment of said work support.

Complete sequence of operations

Assuming that the work, such as a gear wheel to be ground, has been properly mounted on the work holder and proper adjustment has been made of said work holder and grinder wheels in relation to said gear, the operations are as follows: From their raised positions, the grinder wheels D and D' are fed downward by the operation of the rams G and G' which actuate the carriages C⁴. This downward feeding movement is controlled by the resistance of the work but the pressure of the grinder wheels against the work can never exceed that determined by the pressure of the hydraulic fluid. Assuming that the grinder wheel D performs its work faster than the grinder wheel D' so that the ram G reaches the lower end of the movement in advance of the ram G', then the carriage for the grinder wheel D will remain stationary until the ram G' has also completed its downward movement. This is for the reason that the latch member T² remains in locking engagement with the lever T' although the dog P² through the mechanism actuated thereby has tensioned the spring pressed plunger T⁴. Just before the plunger G' completes this downward movement, the cam U contacting with the roller U³ will, through the mechanism above described, release the latch T² permitting the lever T' to be moved by the spring pressed plungers T⁴ so as to reverse the valve N'. This will actuate the motor N to reverse the valves M³ thereby admitting pressure fluid to the lower ends of the rams G and G' and actuating the same in an upward direction. After the grinder wheels have been elevated to a point which clears the work, the dog P⁴ contacting with the finger Q² will rock the member Q to operate the valve R and thereby release the pressure fluid in the motor E¹⁰. The spring E⁹ is then free to actuate the member E⁸ and locking dog E⁷ so as to free the disc E⁶ and the gear train E'. Simultaneously the movement of the lever O² and connecting mechanism will operate the valves M¹ so as to restrict flow of fluid through the conduits M and M² thereby slowing the further upward movement of the rams. Also, the valve O' will be operated to move the piston H³ in the hydraulic motor H in a direction for actuating the gear train E' through the medium of the rack H⁴ and pinion H'. The length of travel of the piston H³ has been determined by the adjustment of the stop H⁶ and is just sufficient to move the gear train E' the required distance for indexing. While this operation is taking place, the continued slow upward movement of the rams will cause the dog P³ to actuate the rocker member S and through the connecting mechanism actuate the valves M³ reversing the same and starting the rams on their downward movement. This continues at slow speed until the dog P⁴ engages the finger Q³ rocking the member Q and actuating the valve R so as to restore fluid pressure on the motor E¹⁰ which moves the dog E⁷ into locking engagement with the disc E⁶. This movement will also through the connections described

reverse the valve O' so as to return the piston H³ to its original position. During this movement, the rack H⁴ engaging the pinion H' will rotate the latter in the reverse direction but the one way clutch H⁷ will permit this movement without disturbing the gear train E'. The valves M' will also be moved to their open position removing the restriction to the flow of fluid through the conduits M and M². This completes the cycle which is repeated without interruption.

In the progress of the work, the teeth on one side of the gear wheel are successively ground by one of the grinder wheels and simultaneously the teeth on the other side of the gear wheel are successively ground by the other grinder wheel. When the tooth first ground by one of the grinder wheels comes in registration with the other grinder wheel, the latter is fed inward to take a second cut and this is repeated until the teeth are ground to their final form. It is thus apparent that the indexing of the wheel always progresses in one direction and the same teeth are alternately ground by the two grinder wheels. However, for the final finishing cycle, it may be desirable to withdraw one of the grinder wheels from operative relation to the work and to grind all of the teeth by a single wheel. This avoids any variation such as might be due to a minute inaccuracy in the setting of one grinder wheel in relation to the other.

To regulate the speed of travel of the rams G, I preferably provide valves M⁹ which variably restrict the supply of fluid from the pumps L and L' to the valves M³. The valves M³ and M⁹ are preferably within the casings M⁶ located at the front of the machine. A lever M⁷ is connected to operate the valve M⁹ and a lever M⁸ is connected to operate the valve M³ in case for any reason it is desired to reverse it manually. However, normally the valves M³ are automatically operated.

For adjusting the grinder wheels toward the work the carriages C⁶ are moved on the ways C⁵ through the operation of mechanisms not fully shown actuated by hand wheels C⁸. There are also preferably micrometer gauges C⁹ which indicate the exact amount of movement of the grinder wheels toward or from the work.

Trimming mechanism

The grinding wheels D and D' must be trimmed to exactly the same cross sectional contour and this trimming must be repeated from time to time to restore the form. For this purpose, I employ a single trimming mechanism which may be successively placed in operative relation to each of the grinder wheels and in exact relation to indexed positions of the work. As specifically shown, this trimming mechanism is mounted on a carrier frame V which has a hinged or pivotal connection V' to the upper ends of a pair of posts V² rising from the base in rear of the work holder. The frame V has a forwardly extending portion V³ and a rearwardly extending counterbalancing portion V⁴. Pivotedly connected to the portion V³ in axial alignment with the work holder is an extension member W having a slideway W² for adjustably supporting a casing W² containing the trimming mechanism. The trimming mechanism may be of any suitable construction such as a pantograph mechanism carrying diamond trimmers and controlled by templets. However, as the specific construction of this mechanism forms no part of the instant invention, it need not be described in detail.

In the trimming of grinder wheels for use in grinding gears, it is customary to fashion the cross sectional contour of the grinder wheel so as to correspond to the interdental space of the gear. There are, therefore, separate trimmer points for the opposite sides of the wheel which trace either exactly similar curves or slightly modified curves according to the contour desired. Where the curves are not exactly the same, it is essential that in arranging the trimmer in operative relation to the respective grinder wheels, the trimmer points should be in the same relation in each position. In other words, the same trimmer should trim the side of each grinder wheel which forms the same side of the gear tooth. Such arrangement I obtain by swinging the extension member W about the pivot W^3 from a position where the trimmers are in operative relation with one grinding wheel to the position where they are in operative relation to the other grinding wheel. If the two grinding wheels are in the same plane as is the case where the number of teeth in the gear is even, then this adjusting movement will be through an angle of 180° . On the other hand, if the grinding wheels are not in the same plane as where the number of gear teeth is odd, then the angle of adjustment is less than 180° by an amount equal to one-half the circular pitch of the tooth to be ground. It is, of course, essential that these two positions should be very exact in their registration with indexed positions of the work as otherwise the teeth ground by one of the grinder wheels would not properly index with those ground by the other wheel.

To accomplish the result just described, the member W extends radially outward from the axis of the pivot W^3 a distance at least equal to the radius of the maximum size of gear wheel to be ground. This permits of adjusting the casing W^2 and the trimmer points into operative relation to the grinder wheels when the latter are adjusted for grinding gear wheels of different diameters. The trimmers are exactly positioned by one or more arms W^4 extending from the member W to engage one or more cooperating stops. As specifically illustrated, there are two arms W^4 which alternately engage a single stop lug V^5 on the portion V^3 of the member V . The arms have at their outer ends bearing faces W^5 for engaging opposite faces of the lug V^5 when the member W is rotated on its pivot through an angle of 180° . For smaller angular adjustment, exchangeable gauge blocks V^6 are used, each of these corresponding to one-half the circular pitch of the particular gear being ground. After each trimming operation, the carrier frame V may be turned upward to withdraw the trimming mechanism from interference with the grinder wheels.

To accurately set the grinder wheel D' for grinding gear wheels having an odd number of teeth, I preferably proceed in the following manner: Both grinder wheels D and D' are first trimmed to the same contour as previously described. The grinder wheel D is next operated to grind one tooth or interdental space of the gear wheel, the other grinder wheel D' being withdrawn from contact with the work. The work holder is then indexed around to the position which is nearest to 180° from the position in which this first tooth was ground. The mounting for the grinder wheel D' is then adjusted about the axis of the work holder to bring said wheel into exact registration with the ground tooth. The accuracy of this registration is easily determined by feeding the grinder

wheel D' into contact with the work and observing whether or not both sides of the grinder wheel touch the work simultaneously, this being shown by the sparks produced on the contact.

5 If one side of the wheel touches the work before the other, further advancement of its mounting is required to bring the wheel in exact registration. There are, of course, other methods of accurately setting the wheel but this one is easily 10 performed.

What I claim as my invention is:

1. In a grinding machine, the combination with a rotary work holder and indexing mechanism for intermittently rotatively advancing the 15 same to successive exactly predetermined positions in a cycle, of a plurality of similarly formed grinder wheels mounted in operative relation to the work in registration with spaced indexed positions thereof, a trimming mechanism, a carrier for said trimming mechanism adapted to transfer the same into operative relation successively with each of said grinder wheels, and means for exactly registering said trimming mechanism with the indexed position of said 20 work holder in each of the grinding positions.

2. In a grinding machine, the combination with a rotary work holder and indexing mechanism for intermittently rotatively advancing the same to successive exactly predetermined 25 positions in a cycle, of a plurality of similarly formed grinder wheels mounted in operative relation to the work in registration with spaced indexed positions thereof, means for adjusting one of said grinder wheels in relation to the 30 other to correspond to changes in indexing, a trimming mechanism, a carrier for said trimming mechanism adapted to transfer the same into operative relation successively with each of said grinder wheels, and means for exactly registering said trimming mechanism with the indexed 35 position of said work holder in each grinding position, said registering means being adjustable to correspond with changes in indexing.

3. In a grinding machine, the combination with a rotary work holder and intermittently operated indexing means therefor, of a plurality of similarly formed grinder wheels mounted in operative relation to the work in registration with spaced indexed positions thereof, separate 45 feeding means for advancing each grinder wheel during the performance of its work with a limited pressure permitting variations in the speed thereof in accordance with the resistance of the work, said feeder means alternating with 50 the operation of said indexing mechanism, and means for synchronizing the feeding of said grinder wheels between successive operations 55 thereof.

4. In a grinding machine, the combination with a rotary work holder and intermittently operated indexing means therefor, of a plurality of similarly formed grinder wheels mounted in operative relation to the work in registration with spaced indexed positions thereof, separate 60 reciprocating hydraulic motors for respectively feeding said grinder wheels transversely of the work with a limited pressure in the performance of their grinding operations, said motors permitting variations in the feeding speed of the 65 respective grinder wheels in accordance with the resistance of the work, and means for delaying the reversal of each hydraulic motor after the 70 completion of its stroke in one direction until the other motor has completed its corresponding stroke thereby synchronizing said motors.

5. In a grinding machine, the combination with a work holder, an indexing mechanism for intermittently advancing the same to successive exactly predetermined positions, of a plurality of similarly formed grinder wheels mounted in operative relation to the work in registration with spaced indexed positions thereof, a trimming mechanism having a pair of trimmers for fashioning opposite sides of said grinder wheels, a carrier for said trimming mechanism adapted

5 to transfer the same into operative relation successively with each of said grinder wheels and with the separate trimmers thereof adapted to engage the corresponding sides of said grinder wheels, and means for exactly registering said trimming mechanism with the indexed position of said work holder in each of the grinding positions.

10

FREDERICK A. WARD.
